PASTE FEED MECHANISM FOR CAN
LABELING AND LIKE MACHINESDavid William Bingham, Brighton, Victoria,
AustraliaApplication September 4, 1946, Serial No. 694,802
In Australia November 21, 1945

4 Claims. (Cl. 216—46)

1

This invention relates to can labelling machines and particularly to that type of machine which includes a track or guideway for rolling the un-labelled cans over a stack of labels which are intermittently raised a distance corresponding to the thickness of a label so that each can may pick up the topmost label on the stack as it passes thereover. The labels are picked up and secured by automatically applying paste to the leading and trailing edge portions of the labels. The can guideway is usually laterally adjustable so that the machine may be adapted to handle cans of various sizes.

It is customary to employ a pump for feeding the paste to the paste applying mechanism and hitherto such a feed pump has usually been adapted for direct operation by the cans as they roll along the track way. Such types of apparatus have not proved to be entirely satisfactory due to the difficulty experienced in reducing the friction in the pump and its actuating mechanism sufficiently to enable it to be effectively operated by the passing cans without impeding their progress.

The primary object of the present invention is to provide improvements in can labelling machines of the kind indicated whereby the cans passing through the machine are adapted to control the operation of a power actuated paste feed pump or the like instead of directly actuating such a pump as hitherto.

Another object of the invention is to provide in can labelling machines of the kind indicated simple and efficient means for regulating the predetermined amounts of paste fed to the paste applying mechanism in accordance with the size of the cans being handled.

Referring to the drawings which form part of this specification—

Fig. 1 is a transverse sectional elevation of apparatus in accordance with one embodiment of the present invention.

Fig. 2 is a plan view of the paste pump unit seen in Fig. 1.

Fig. 3 is a side view of the parts seen in Fig. 1.

Fig. 4 is a sectional plan taken on the line IV—IV of Fig. 3.

Fig. 5 is a side elevation on an enlarged scale showing the improved paste pump control mechanism.

Fig. 5a is a fragmentary cross-sectional view taken on line 5A—5A of Fig. 5.

Figs. 6, 7 and 8 are operative details of the clutch control mechanism for the pump driving means.

2

According to the embodiment illustrated, the improved machine includes a track or guideway 2 along which the cans 3 to be labelled are rolled over a stack of labels 5 on a platform or like support 5a. The latter is provided with any suitable elevating means for intermittently raising the stack a distance equal to the thickness of a label so as to ensure that the topmost label will be picked up by each can as it rolls over the stack. Such platform elevating means is shown for example in my co-pending United States patent application Serial No. 694,804, filed September 4, 1946.

The labels are secured to the cans by applying paste to the leading and trailing edge portions of the labels. Means may be provided for applying spots of paste to each can as it nears the stack so that the paste spots are pressed into contact with the leading edge portion of the topmost label 5 which is thus picked up and wrapped around the can as it rolls over the stack.

Paste may be applied to the trailing edge portion of each label 5 through a hollow paste bar or tube 4 adapted to engage the trailing edge of 25 the topmost label so that as this label is peeled off the stack as aforesaid, it is pulled out from under the paste bar and the pasted trailing edge portion pressed into engagement with the underlying leading edge portion of the label.

30 The paste bar 4 is supplied with paste from a hopper or reservoir 6 by a pump 7 connected by piping 8 with the paste bar. A rotary gear pump is particularly suitable for this purpose.

In accordance with the present invention, means are provided for intermittently operating the pump 7 so as to ensure that the paste is applied once only to the trailing edge portion of each label. For this purpose the pump operating means may include pawl and ratchet drive mechanism having control means associated therewith which is adapted to be actuated by each can as it rolls along the track way.

The pawl and ratchet mechanism may be mounted on a fixed support such as a bracket 10 and include a ratchet wheel 11 fitted to the pump shaft 12 and a spring influenced pawl 13 carried by a movable support which is adapted to swing about the axis of the associated ratchet wheel.

50 The pump is adapted to be power driven and for this purpose the pawl support may consist of a plate 14 on which the pawl is pivotally mounted as at 16, the plate being also mounted upon the pump shaft and pivotally connected as 55 at 17 to a reciprocating connecting rod 18 which

is power driven in any suitable manner. The spring influenced pawl normally engages the teeth of the ratchet wheel and partly rotates the pump shaft during the swinging movements of the pawl supporting plate.

Associated with the pawl and ratchet driving mechanism is clutch or like means for automatically engaging and disengaging the pawl from its ratchet wheel in synchronism with the passage of the cans along the track way. Such clutch means may comprise a latch member for example, in the form of a pivoted latch plate 21 pivotally mounted as at 29 upon the brackets 10 and which may be adapted normally to swing across the path of the pawl 13 so as to maintain the pawl out of engagement with the ratchet wheel. For this purpose the pawl may be provided with an extension or tail piece 22 adapted to be engaged by the latch plate.

As the trackway 2 is preferably adjustable so that the machine may handle different sized cans, the machine also includes feed control means for the pump 7 so that a predetermined amount of paste may be applied to the trailing edge portion of each label. Said feed control means may include an adjustable striker member 26 adapted to disengage the pawl 13 from the ratchet wheel, if necessary, before completion of the forward throw of the pawl supporting plate 14 when the desired predetermined amount of paste has been applied to the label.

Any suitable means is provided for adjusting the operative position of the striker 26 so as to vary the distance traversed by the pawl 13 prior to being disengaged from the ratchet wheel 11, thus regulating the pump delivery in accordance with requirements. This adjustment of the striker may be effected by screw means such as a threaded post 27 mounted on a stationary support 28 and provided at one end with an enlarged head or the like 29 for turning and connected at its opposite end as at 31 to the striker for swinging the latter as required about a pivotal mounting 32.

The aforesaid latch plate 21 may be provided at one side with a gap or recess 33 so that the latch plate may swing into and out of engagement with the pawl irrespective of the operative position of the striker arm. The latch plate may also be provided with a finger or the like 34 overhanging the gap, while its pivotal mounting may be located off centre so that the lower portion of the plate may normally tend to swing across and engage the pawl under the influence of gravity.

In combination with the foregoing are means for swinging the latch plate 21 out of engagement with the pawl 13 as each can passes along the track way. Such latch control means may comprise a spring influenced trigger plate 36 mounted within the track way 2 so as to be engaged by each can as it passes. The trigger plate is connected, for example by means of a push rod 37, with the finger 34 on the latch plate whereby depression of the trigger plate by a can automatically swings the latch plate clear of the pawl and permits the latter to engage the ratchet wheel and partially rotate the pump shaft for supplying a predetermined quantity of paste to the topmost label on the stack.

In use, the power driven pawl supporting plate 14 is continuously oscillating while the labelling machine is in use but the pump 7 remains inoperative until the latch plate 21 is tripped by an onrolling can, thus permitting the pawl 13 to engage its ratchet wheel 11 under the influ-

ence of its spring for delivering the desired predetermined amount of paste to the topmost label. The operative positions of the pawl 13 and its associated latch plate 21 and striker 26 are seen more clearly in Figs. 6, 7 and 8 of the drawings.

In Fig. 6 the pawl is shown at the commencement of its forward throw with the tail piece 22 about to engage the latch plate. Fig. 7 shows the pawl at the completion of an inoperative forward throw showing the tail piece still in engagement with the latch plate. The pump 7 has, of course, remained inoperative during such movement of the pawl. Fig. 8 shows the pawl in its operative position at the completion of a forward stroke for actuating the pump. The latch plate is clear of the tail piece and thus permits the pawl to remain in engagement with the ratchet wheel throughout the forward throw of the pawl supporting plate 14 unless the striker has been adjusted to engage the tail piece 22 of the pawl and thus disengage it from the ratchet wheel before completion of said forward throw.

It will be readily appreciated that when smaller cans are being handled, the predetermined quantity of paste supplied to each label may be suitably reduced simply by manually turning the screwed post 27 for adjusting the striker arm 26 to release the pawl before completion of its full forward throw.

It is to be understood that various alterations, modifications and/or additions may be incorporated in the foregoing construction and arrangement of parts without departing from the ambit of the invention as defined by the appended claims.

Having now described my invention, what I claim as new and desire to secure by Letters Patent is:

1. In labelling machines including a rotary feed pump for supplying paste to paste-applying means, pump-driving mechanism comprising a ratchet wheel on the pump shaft, a power operable plate mounted upon the pump shaft to oscillate thereon, a spring-influenced pawl mounted on said plate and biased into engagement with said ratchet wheel, a latch member pivotal into the path of said pawl for disengaging the pawl from the ratchet wheel, and latch control means operable by articles as they pass through the labelling machine and operative to swing said latch member from the path of said pawl to permit the latter to engage said ratchet wheel.

2. Apparatus according to claim 1 wherein said power operable pawl supporting plate is pivotally mounted upon the pump shaft so as to oscillate thereon and said pivoted latch plate is mounted upon a fixed support and pivoted off centre so that it tends to normally swing into engagement with a tail piece on said pawl for disengaging the pawl from its ratchet wheel during the forward throw of said pawl supporting plate.

3. In operable labelling machines, a rotary feed pump for intermittently supplying paste to paste applying means, pawl and ratchet driving means for the pump and comprising a ratchet wheel on the pump shaft, a spring influenced pawl pivotally mounted upon a pawl supporting plate which is also carried by said pump shaft, power driven mechanism for oscillating said pawl supporting plate, a pivoted latch plate mounted upon a fixed support for swinging into and out of engagement with said pawl, a striker member for engaging said pawl to disconnect

it from the ratchet wheel, a manually operable threaded post carried by a fixed support and connected to said striker member for adjusting the operative position thereof, and latch control means mounted on the machine frame so as to extend between a trackway and said latch member whereby each article passing along said trackway swings the latch member clear of said pawl and permits the latter to engage the ratchet wheel.

4. In labelling machines including a rotary pump for feeding paste to paste-applying means and a power-actuated mechanism for intermittently operating the said pump, feed control means for regulating the amount of paste delivered by said pump which comprises a ratchet wheel on the pump shaft, a pivoted pawl having a tail piece and cooperating with said ratchet wheel for operating said pump, an intermediately pivoted striker member having one end operatively positioned in the path of said pawl tail

6

piece to disengage said pawl from said ratchet wheel, and adjusting means comprising a threaded post mounted upon a fixed support and provided at one end with a turning head and at its opposite end with a pin and slot connection with the other end of said striker member to selectively position said member relative to the pawl tail piece.

DAVID WILLIAM BINGHAM.
